United States Patent

Des. 240,112
Patented June 1, 1976

240,112

PRESSURIZED DISPENSING CONTAINER

William J. O'Neil, Jr., Cincinnati, Ohio, assignor to The Drackett Company, Cincinnati, Ohio

Filed Dec. 18, 1974, Ser. No. 533,859

Term of patent 14 years

Int. Cl. D9—01

U.S. Cl. D9—9

Fig. 1.

Fig. 2.

Fig. 3.

Fig. 4.

FIG. 1 is a perspective view of a pressurized dispensing container embodying my new design;

FIG. 2 is a side view thereof;

FIG. 3 is a top plan view thereof;

FIG. 4 is a bottom plan view thereof;

FIG. 5 is a perspective view with the overcap removed;

FIG. 6 is a side view thereof; and

FIG. 7 is a top plan view thereof.

I claim:

The ornamental design for a pressurized dispensing container, as shown.
